Des. 181,634
Patented Dec. 10, 1957

181,634

INFANT'S BATH TUB OR SIMILAR ARTICLE

William H. Englehart, Kokomo, Ind., assignor to The Fabri-Form Company, Byesville, Ohio, a corporation of Ohio

Application October 19, 1956, Serial No. 43,414

Term of patent 3½ years

(Cl. D4—4)

FIG. 1.

FIG. 2.

FIG. 3.

FIG. 4.

FIG. 6.

Fig. 1 is a top plan view of an infant's bath tub or similar article showing my new design;

Fig. 2 is a bottom plan view;

Fig. 3 is a side elevational view;

Fig. 4 is an elevational view looking toward one end of the infant's bath tub or similar article;

Fig. 5 is a similar view looking toward the opposite end thereof; and

Fig. 6 is a medial longitudinal vertical sectional view taken through the infant's bath tub or similar article.

I claim:

The ornamental design for an infant's bath tub or similar article, substantially as shown.
